UNITED STATES PATENT OFFICE.

HENRY ERICSSON, OF CHICAGO, ILLINOIS.

FORM FOR CONCRETE GIRDER CONSTRUCTION.

1,152,307.

Specification of Letters Patent.

Patented Aug. 31, 1915.

Application filed July 18, 1910. Serial No. 572,428.

To all whom it may concern:

Be it known that I, HENRY ERICSSON, a citizen of the United States, residing at Chicago, in the county of Cook and State of Illinois, have invented certain new and useful Improvements in Forms for Concrete Girder Construction, of which the following is a description.

My invention relates to means for forming a girder or similar parts in building construction and providing for the proper support of the joist or other adjacent portions of the structure during the forming and hardening or setting of the girder.

15 The object of my invention is to provide a simple, convenient, cheap and durable device of the kind described which is sufficiently portable and adjustable to be employed repeatedly in constructions of the

20 same general class or character.

To this end my invention consists in the

novel construction, arrangement and combi-

nation of parts herein shown and described

and more particularly pointed out in the

25 claims.

In the accompanying drawings wherein

like or similar reference characters indicate

like or corresponding parts: Figure 1 is a

vertical transverse section of my device.

30 Fig. 2 is an enlarged detail showing the

construction and arrangement of the side of

the mold and associated parts.

In the preferred form shown, a suitable

bed piece 1 is provided arranged to rest

35 upon the floor or other portion of the struc-

ture being constructed for supporting the

forms and an up-right or form supporting

means is provided arranged to rest upon

the bed piece. As shown the form support-

40 ing means consists of a pair of timbers 2-2

of suitable length connected near their lower

ends by a tie 3 rigidly attached to each and

at their upper ends by a cross bar 4 also

rigidly secured to the timbers 2-2 with both

45 ends projecting beyond the timbers. A pair

of braces 5-5 or equivalent means are rigi-

dly secured to the timbers 2-2 near the

cross tie 3 and each extends upward and lat-

erally to the upper end of the opposite tim-

50 ber where they are securely attached to the

timbers and to the cross bar 4. A portion

near the end of each brace preferably pro-

jects above the cross bar 4 with the inner

face or edge of the brace formed and posi-

55 tioned substantially at right angles to the

bar. Suitable adjusting means are pro-

vided, as for example, the wedges 6-6, at the lower end of the timbers 2-2 for adjusting the vertical position of the cross bar 4 to compensate for any slight variations or irregularities in the surface upon which the bed piece 1 is resting.

60 My improved form for molding the girder is arranged to rest upon the cross bar 4 and preferably consists of a bottom part 8 adapt-

65 ed to form the bottom face of the girder which preferably corresponds accurately in width with the columns 9 for supporting the girder. The sides of the mold are each composed of an L shaped part preferably

70 formed of two planks 10 and 11 positioned at substantially right angles with each other to form an L. The plank 10 rests upon the cross bar 4 and is substantially parallel to the common plane of the cross bars 4 and

75 in the same plane as the bottom part 8 of the mold. A transversely curved plate or side member 12 is provided, resting upon and rigidly secured to the free edges of the L shaped part 10-11 adapted to serve as a

80 side member for the mold and to control the form of this portion of the girder. In assem-

85 bling the mold the supporting means are arranged in position and the bottom part 8 is fitted into the spaces between the columns. The L shaped side parts 10-11 are next

85 placed in position at each side of the bottom part 8 and the curved side member 12 is rigidly secured to the free edges of the parts 10 and 11. A wedge 14 or other adjusting

90 and locking means is next inserted and forced into the space between the projecting part of each brace 5 and plank 11 thereby clamping the bottom part 8 between the side members 12 and providing a satisfactorily

95 tight joint between the bottom part 8, the sides of the column 9 and the parts 12. The parts 12 are each preferably continuous for any desired length of girder. When thus

100 constructed it is obvious that suitable ceil-

ing or floor forms may be mounted upon the upper edge of the parts 11 for constructing a concrete floor or ceiling, or if desired, suitable joist or other supporting timbers

105 may rest upon this portion of the mold while the girder is being constructed and while the concrete forming the girder is

110 setting or hardening, after which the wedges 14 and 6 may be removed permitting the supporting means and the girder form to be taken down and moved into some other position.

It is obvious that the several parts of my device as herein shown and described are suitable for ordinary structures, but that the several parts may be changed, as may be desired, to adapt my device for use in structures of special design or construction, as for constructing girders for bridges or similar structures.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. A device of the kind described, comprising supporting means, in combination with a form resting upon said supporting means comprising two curved sheet metal side members each extending upward and outward, said supporting means having two flat faces at an angle to each other extending longitudinally of and engaging the edges of said side members, a bottom part positioned between said side parts, and means for supporting said side members and forcing the same against said bottom part and locking the parts in position.

2. A device of the kind described, comprising supporting means, a cross bar at the upper end of said supporting means, and means rigidly engaging said cross bar near its ends with a part projecting upward at substantially right angles to said bar, in combination with a form resting upon said cross bar comprising two curved side members each extending upward and outward from said cross bar, a bottom part positioned between said side parts, and means for engaging the edges only of said side part supporting and forcing the same against said bottom part and locking the parts in position.

3. A device of the kind described, comprising supporting means, in combination with a form resting upon said supporting means comprising two transversely curved members extending upward and outward from said supporting means, a bottom part positioned between said side parts and means engaging the lower margin of each of said side parts to support the same and force them against said bottom part, means for supporting the upper edges of said curved members and means for locking the parts in position.

4. A device of the kind described, comprising a plurality of supporting means and a cross bar at the upper end of each of said supporting means, in combination with a form resting upon said cross bar comprising two L shaped parts, each having one side parallel to the common plane of said cross bars and a side part resting upon the

free edges of said L shaped part and extending upward and outward from said cross bar, a bottom part positioned between said side parts and means for forcing said side parts against said bottom part and locking the parts in position.

5. A device of the kind described, comprising supporting means, in combination with a form comprising two sheet metal side members each extending upward and outward with the plane of the longitudinal margins of each side member at substantially right angles to each other, said supporting means having two flat faces at an angle to each other extending longitudinally of and engaging the edges of said side members, a body part positioned between said side members and means for forcing said side members against said body part.

6. A device of the kind described, comprising supporting means, in combination with a form resting upon said supporting means, comprising two transversely curved side members each extending upward and outward in the form of a quadrant supporting means at the margin only of said side members and arranged to support a plurality of ceiling forms in position, a bottom part positioned between said side parts, and means for forcing said side members into position against said body part.

7. A device of the kind described, comprising supporting means, in combination with a form resting upon said supporting means comprising two transversely curved side members each extending upward and outward in the form of a quadrant from said supporting means with an L-shaped part engaging the edges only of said side member arranged to support a plurality of ceiling forms in position, a bottom part corresponding in width to the width of the column for supporting the girder, positioned between said side parts and means for supporting said side parts and forcing them against said bottom part and the sides of said column, whereby said side members co-operate jointly with said bottom part and the side of said column to form a mold for said girder.

8. A device of the kind described, comprising a plurality of supporting means and a cross bar at the upper end of each of said supporting means, in combination with a form resting upon said cross bar comprising two L shaped parts each with one side positioned parallel to the common plane of said cross bars and a side part resting upon the free edges of said L shaped parts and extending upward and outward from said cross bar, a bottom part corresponding in width to the column for supporting the girder positioned between said side parts and means co-operating with said braces for forcing said side part against said bottom part.

part and the sides of said column and locking said parts in position, where said side members coöperate jointly with said bottom part and the side of said column to form 5 a mold for said girder.

9. A device of the kind described, comprising a plurality of supporting means, a cross bar at the upper end of each of said supporting means and braces engaging said 10 cross bar near its ends with a part projecting at substantially right angles to the bar, in combination with a form resting upon said cross bar comprising two L shaped parts each positioned with one side parallel to the 15 common plane of said cross bars and a transversely curved side part resting upon the free edges of said L shaped part extending upward and outward from said cross bar arranged to support a plurality of ceiling 20 forms in position, a bottom part positioned between said side parts and means coöperating with said braces for forcing said side

parts against said bottom part and locking the parts in position.

10. In a device of the kind described, a 25 form comprising a cross bar, two curved side members extending upward and outward from said cross bar, said supporting means having two flat faces at an angle to each other extending longitudinally of and 30 engaging the edges of said side members, a bottom part positioned between said side parts, and means coöperating with said cross bar for forcing said side parts against said bottom part and locking the parts in position. 35

In testimony whereof, I have hereunto signed my name in the presence of two subscribing witnesses.

HENRY ERICSSON.
